CALCULATING INSTRUMENT

Arthur F. Winterfeldt, Montgomery County, Md.

Application May 12, 1952, Serial No. 287,412

10 Claims. (Cl. 235—88)

(Granted under Title 35, U. S. Code (1952),
sec. 266)

1

The invention described herein may be manufactured and used by or for the Government of the United States of America for governmental purposes without the payment of any royalties thereon or therefor.

This invention relates to calculators, and more particularly to a calculating instrument which is utilized to solve a number of problems involved in the layout of animation motion pictures.

Many peculiar problems arise in the production of animation motion pictures. Generally, an animation motion picture is produced by photographing a series of separate pictures on a continuous length of film. The pictures are generally drawn by hand. Motion in the objects is produced by having the objects positioned somewhat differently in each successive picture there being sixteen separate photographs or frames per foot of film. When the continuous roll of film is developed and displayed through a motion picture projector, the different pictures are seen faster than the human eye can detect and therefore the objects appear to move.

In the art, means have been provided for causing movement of objects other than by the drawing of separate pictures, particularly straight line movement. This is accomplished by mounting a background drawing over a source of light and providing a pair of parallel sliding bars, known in the art as pan bars, on opposite sides of the drawing. That is, one bar may be mounted adjacent and parallel to the top edge of the drawing and the other bar mounted adjacent the bottom edge. The object to be moved is drawn on a transparent sheet of Celluloid which is adapted to be secured to the pan bars. This transparent sheet of Celluloid is known in the art as a pan cel. Therefore, the object which is to move is placed in its initial position and a photograph is made. The pan bars are then moved to position the object in a new position and a second photograph is taken. This process is repeated until the object is in its final position for the particular movement desired. In the layout stage, it is necessary to compute how far to move the pan bars in hundredths of an inch each time a separate photograph is made in order that the object will move a certain distance in inches over the background during the filming of a certain number of feet of film. The mental calculation of this amount of movement is normally carried out by the animator himself and is both time consuming and often erroneous. Approximately 25% of the animator's time is required for calculations. Further, should an error in the calculations occur, it results in time lost on production,

2

costly and tedious camera work done for nothing, and perhaps make it necessary to revise and redraw the layout and art work.

It is an object, therefore, of the present invention, to provide a calculating instrument to solve the above mentioned problem which eliminates error and saves many man hours work, it being only necessary to make two settings based on the known information and reading the answer.

Another problem involved in animated motion picture production is in the determination of the length of pan cel to accomplish the amount of movement which will be necessary. An analogous problem is the determination of the length of panoramic background so that the object can begin its movement at one point in the drawing and end its movement at another point. The animator knows the number of feet of film in which the movement must be made. For example, this may be determined by the length of narration which is to be used during the movement. He also knows approximately the rate of movement necessary to create a smooth moving effect. To have to convert the number of feet of film to the number of separate pictures or frames and multiply this by the rate of movement in hundredths of an inch is also time consuming and often results in erroneous calculations. The many times the calculations must be made during the production of a film make it imperative that a quick and efficient means be available for the calculations. This is emphasized by the fact that by their very nature animated motion pictures are very expensive productions.

It is another object of the present invention to provide a calculating instrument which solves the problem mentioned in the paragraph above by merely manipulating the parts of the instrument until the known information has been placed in the instrument and then reading the answer.

Under special circumstances it may be desired to make the straight line movement non-parallel to the top or bottom edges of the panoramic background. For example, it may be desired to have an aircraft dive on a ship which is drawn on the background. This makes it necessary to move the pan bars until they parallel the dive angle of the aircraft. Under these circumstances, however, the pan bars will cut opposite corners of the panoramic background drawing. Since the camera is originally positioned to take in the entire field of the drawing, it will also take in portions of the pan bars. Therefore, the camera must be repositioned to take in a smaller field

which does not include the pan bars. In animation work the size of field which the camera can take may be numerically represented. For example, a camera may have an aperture capable of photographing a maximum size drawing having the dimensions of eight and one-half inches by twelve inches. This may be known as a "twelve" field, taking its identity from the length of the long side, and is the maximum field for the camera. This same camera may be moved closer to the drawing and have a minimum field which is proportionally smaller, which may be given a smaller numerical value. For example, this may be known as a "four" field wherein the length of the longest sides of this minimum field is four inches. The camera support may be calibrated so that the operator can tell when the camera aperture is the correct distance from the drawing for these two fields and for all fields therebetween. Therefore, when the camera is set for a "twelve" field and the pan bars have been tilted a certain number of degrees to provide the aircraft diving effect as aforementioned, the camera must be lowered so that the aperture takes in a maximum size field which does not include the pan bars. Ordinarily the problem is solved by experimenting with different camera positions until a correct position is found.

It is another object of this invention to provide a calculating instrument which provides the operator with the maximum camera field he can use with a given amount of tilt of the pan bars in degrees, and vice versa.

Still another object of the present invention is to furnish a calculating instrument which solves the problems aforementioned and which includes a first mentioned circular disc having radially extending columns of information arranged thereon on each side thereof, second and third circular discs mounted on each side of said first mentioned disc, and a frame means surrounding said discs about a diameter thereof, said frame means having a securing means which extends therethrough and through central apertures in said discs for rotatably mounting said discs.

A further object of the invention is to provide an instrument as aforementioned wherein the frame means is transparent with a hairline extending the length thereof with which information printed on said discs is adapted to be oriented, and a plurality of spirally arranged windows on the second and third discs which permit the reading of a correct answer from the radially extending columns on the first disc for a given orientation of the second and third discs.

Other objects and many of the attendant advantages of this invention will be readily appreciated as the same becomes better understood by reference to the following detailed description when considered in connection with the accompanying drawings wherein:

Fig. 1 is a plan view of a preferred embodiment of the calculating instrument with a portion thereof broken away to show further details;

Fig. 2 is a plan view of a modified form of the instrument also having parts thereof broken away to provide greater clarity;

Fig. 3 is a sectional view taken on lines 3-3 of Fig. 1;

Fig. 4 is a sectional view taken on lines 4-4 of Fig. 1;

Fig. 5 is a sectional view taken on lines 5-5 of Fig. 2;

Fig. 6 is a sectional view taken on lines 6-6 of Fig. 3;

Fig. 7 is an enlarged view of the broken away portion of Fig. 1; and

Fig. 8 is an enlarged view of the broken away portion of Fig. 2.

Similar reference characters represent similar parts throughout the specification.

As seen in Figs. 1, 2 and 3, the instrument comprises a pair of spaced apart rectangular frame members 10 and 11 having spacing members 12 and 13 between the ends thereof. The frame members may be fused or otherwise secured to the spacing members. The frame members are constructed preferably of a transparent material such as plastic and include the longitudinally extending centerlines or hairlines 14 and 15, respectively.

A first mentioned circular disc 16 is mounted between the two frame members with the periphery of the disc closely adjacent the inside edge of the spacing members. A second mentioned circular disc 17 of lesser diameter than disc 16 is mounted adjacent one side of disc 16 and frame member 10. A third mentioned circular disc 18, also of lesser diameter than disc 16, is mounted adjacent the other side of disc 16 and frame member 11. All three discs and the two frame members are provided with central apertures and a pivot pin 19 extends therethrough to provide a rotatable mounting for the discs. As shown in Fig. 6, pin 19 preferably is in the form of an internally threaded sleeve 20 having a flange 21 at one end thereof. A screw 22 is adapted to be received by the sleeve, there being a head 23 on one end of the screw. Seats are provided in members 11 and 12 for the reception of flange 21 and head 23, respectively.

The periphery of circular disc 16 is marked on each side thereof with fifty short radially extending lines which are spaced equal distances from each other. Each line is marked with an identifying numeral in a series beginning with $\frac{1}{2}$ and extending through 25, each succeeding line in a clockwise direction from the beginning on one side, as seen in Fig. 7, and a counterclockwise direction from the beginning on the other side, as seen in Fig. 8, being given a value larger by $\frac{1}{2}$ than the preceding numeral. These numerals represent feet of film. On the side of disc 16 adjacent disc 17, as seen in Figs. 1 and 7, these numerals on the periphery form a scale 24.

A column of numerals illustrated by the reference character 26 extends from the center of the disc to each of the fifty aforementioned film footage representations on scale 24. Each column includes the numerals which will give the correct solution to a problem which is to be solved by this side of the instrument. As shown in Figs. 2 and 3, a similar number of columns of numerals, illustrated by the numeral 27, is provided on the side of disc 16 adjacent disc 18. The numerals in each column are chosen to give the correct solution to problems which are to be solved by this side of the instrument. In the columns on each side of the instrument only representative numerals have been given because of the obvious difficulty of illustrating each series of numbers in the fifty columns on each side of the instrument. As will be made clear as the description proceeds, however, a person skilled in the art will be able to compute the proper numbers to be placed in the columns. It will be noted that circular disc 16 serves both forms of the invention since one side thereof is used

with the form of the invention shown in Fig. 1 and the other side is used with the form of the invention shown in Fig. 2. In other words, the modifications have a common member. It is obvious that the forms of the invention shown in Figs. 1 and 2 could be as separate instruments but for the animator both sides can be used and therefore they are made into a unitary instrument for his convenience and for the saving of materials.

Circular disc 17, as shown in Figs. 1 and 3, is of a lesser diameter than disc 16, the periphery thereof lying closely adjacent the film footage numerals on disc 16 in a manner to permit the viewing of said numerals. Disc 17 is preferably of an opaque material so that the entire columns of numerals on disc 16 will not be visible therethrough. To permit the viewing of particular numerals in the columns, however, a series of spirally arranged rectangular windows 28 is provided. These windows may be in the form of actual openings in the disc, as seen in Fig. 4, or may be transparencies therein. The size of the windows is regulated by the size of the numerals in columns 26. While the windows have been shown to be of rectangular configuration, it is obvious that they could be oval or of any shape which would permit the reading of only one numeral of a series in a particular column. As was noted above, the windows describe a spiral which begins near the mounting pin and extends to the outer periphery of the disc, each window being equally spaced from the windows adjacent thereto. Each window in the series is spaced radially from the mounting pin such a distance that each window will center on or permit the viewing of a separate numeral in the series of numerals in columns 26. That is, the window nearest the pivot pin, which begins the spiral, will center on the numerals in the columns nearest to the center pin. The next window in the spiral will read the next numeral outwardly from the aforementioned numeral which is nearest the pivot pin. The succeeding windows will center on succeeding numerals in the column until the last window, which is nearest to the periphery of the disc, centers on the numerals adjacent the periphery of disc 16.

Inscribed on the outer surface of disc 17 is a scale 29, said scale being in the shape of an arc covering substantially the same number of degrees of arc as the spirally arranged windows cover. The scale is marked off with short radial lines, the spacing of which decreases gradually from one end of the scale to the other. The scale is provided with numerals, beginning at one end with $\frac{1}{4}$ and ending with 12, each succeeding marking from $\frac{1}{4}$ being larger by an amount of $\frac{1}{4}$. The relationship between scale 29 and the spirally arranged windows 28 is such that a straight line may be drawn from the $\frac{1}{4}$ mark on scale 29, through central mounting pin 19, and through the center of the window nearest pin 19. Also, a straight line may be drawn from the 12 mark on scale 29, through the central mounting pin 19, and through the center of the window nearest the periphery of disc 17. Further, a straight line may be drawn from succeeding markings after the $\frac{1}{4}$ mark on scale 29, through pin 19, and through succeeding windows after the window nearest pin 19. This relationship between scale 29 and windows 28 is caused by the fact that as the windows extend spirally outwardly, the actual distance between the windows remains the same but the angle in degrees between radial lines

from pin 19 through the center of the windows decreases. Therefore, on scale 29, which is an arc with all points equidistant from pin 19, the spacing of the markings gradually decrease from one end to the other. As denoted in the legend to scale 29, the numerals on the scale represent inches, this being the number of inches on the drawing through which the object is to move.

The operation of this side of the instrument 10 which includes disc 17 will now be explained in detail. As stated earlier the animator will know the number of feet of film. This is most frequently found by knowing the number of seconds of a narration, during which the movement 15 occurs. By multiplying the number of feet of film used per second by the number of seconds, the footage is obtained. Disc 16 is then rotated until the mark denoting the number of feet obtained above its placed under one end of centerline 14. Then, holding frame member 14 and disc 16 stationary, disc 17 is rotated until the mark on scale 29, denoting the number of inches which the object is to move on the drawing, is placed under the other end of centerline 14. 20 With these settings, the answer is shown through the window 28 which is under the said one end of centerline 14. The answer is in hundredths of an inch and tells the operator how much to move the object and pan cel between photographs. 25 The reason for the relationship between which end of centerline 14 is to be placed over the footage scale, the inch scale, and the window showing the answer, is that under the settings aforementioned all the numerals in the problem which 30 are known, and the answer, may be read in an upright position.

From the above it will be apparent that from any known footage over which a known amount of movement in inches is to take place, the animator can determine how much the object should be moved in hundredths of an inch between separate photographs. Since the numerals in columns 26 have not been given in detail the means of computing them will be given. By way of example the column under the footage numeral $1\frac{1}{2}$ will be chosen for calculation. By placing numeral $1\frac{1}{2}$ under one end of centerline 14 and numeral $\frac{1}{4}$ on scale 29 under the other end of said centerline, the window nearest pin 19 will be 35 centered over the lowest numeral position in the column. The numeral to be placed herein may be solved by the following equation:

$$(1) \quad OM_t = \frac{OM_t}{(FL)(16)}$$

where

OM_t =object movement on the drawing in hundredths of an inch per frame of film;

OM_t =total object movement on the drawing in hundredths of an inch;

FL =film length in feet over which movement takes place; and

16=a constant which is the number of frames per foot of film.

With the settings above OM_t equals $\frac{1}{4}$ inch or 25 one-hundredths of an inch, and FL equals $1\frac{1}{2}$ feet. Substituting these values in Equation 1 the following is obtained:

$$70 \quad OM_t = \frac{25}{(1\frac{1}{2})(16)} = 1.04 \text{ hundredths of an inch}$$

This number is rounded off and is placed in the column as 1. To compute the next numeral in the column it is but necessary to use the next

numeral in scale 29, namely $\frac{1}{2}$ in place of $\frac{3}{4}$ used above. Successing numerals in the column are computed by substituting successing numerals of scale 29 in the equation. The remaining columns are computed in an identical manner. It will be noted that all of the columns do not extend the same distance from the periphery toward pin 19. This is due to the fact that the values become so low as to be unusable. That is, the incremental movement of the pan bars is limited to a certain minimum value on the column.

While the scale denoting film footage is limited to 25 feet, it is obvious that larger footage could be sought for. For example, if a movement of 6 inches on the drawing is to occur in 50 feet of film it would only be necessary to take one-half of each amount and compute this on the instrument, thus obtaining the correct answer. This is made possible because of the ratio relationship between the numerals on scale 29 and the peripheral footage scale numerals. It will also be apparent that with a known amount of movement per frame and a known total movement, the footage of film required could be determined. By placing the total movement numeral on scale 29 under one end of centerline 14 and rotating disc 16 until the numeral representing the movement per frame shows up in a window under the other end of said centerline, the footage required will appear on the footage scale under said other end of the centerline.

To find the total movement on the drawing of the object when the incremental movement per frame and the film footage are known, one end of the centerline is placed over the numeral representing the number of feet of film and disc 17 is rotated until the numeral representing the incremental movement per frame appears through a window under the same end of the centerline and the total movement in inches may be read on scale 29 under the other end of the centerline.

On the side of the instrument described above, the animator is not concerned with how smooth the object movement will be. The requisites are that so much movement must take place in a certain number of feet of film. However, there may be instances where the amount of movement per frame of film is important to create a special animated effect. Therefore, it is necessary to compute the total amount of movement and thereby the length of background and the pan cel.

The other side of the instrument, as shown in Figs. 2 and 8, provides a means for determining the total movement of an object in hundredths of an inch. As was noted heretofore, the side of disc 16 herein involved also has a peripheral footage scale, illustrated by the reference character 30, marked from zero to 25 in equal one-half foot increments. Disc 18 is preferably of opaque material and has therein a plurality of spirally arranged windows 31, beginning at a point midway between the mounting pin 19 and the periphery of the disc, and extending to the periphery of the disc. As shown in Fig. 5, these windows are actual cut-outs in the disc. However, as noted above, the windows may be in the form of transparencies in the opaque disc. The windows are spaced from pin 19 so that the window nearest said pin will show the numerals in columns 27 nearest the pivot pin. The succeeding windows outwardly will permit the view of outwardly successing numbers in the columns so that the window nearest the disc periphery will permit the

viewing of the numerals in columns 27 nearest the periphery.

An arcuate scale 32 is provided on disc 18 on the opposite side of pin 19 from windows 31. This scale has all points thereof equidistant from pin 19 and is provided with a number of markings equal to the number of windows, the spacing of said markings gradually decreasing from one end to the other. The markings on scale 32 are numbered, beginning at the end at which the markings are spaced the furthest apart, as follows: $\frac{1}{2}$, 1, 2, 3, 4, 5, 6, 7, 8, 9, 10, 15 and 20. These numbers represent the amount of object movement on the drawing, in hundredths of an inch, per frame of film. The relationship between scale 32 and the spirally arranged windows is brought out by the fact that straight lines through pin 19 may be drawn from the $\frac{1}{2}$ mark on scale 32 to the window nearest said pin and from the 20 mark on scale 32 to the window furthest from said pin.

With the portion of the invention shown in Figs. 2 and 8 and described above, it is a simple matter to determine the total amount of object movement on the drawing, and therefore the length of the pan cel upon which the object must be mounted, when the amount of movement per frame of film, in hundredths of an inch, to create an animated effect, and the number of feet of film over which the movement is to take place, are known. For example, suppose the animator knows that the amount of movement per frame of film must be $\frac{1}{2}$ hundredth of an inch in order to create a desired effect and that the total movement must be completed in 25 feet of film. The centerline 15 at one end is placed over numeral 25 on scale 30 while the other end of the centerline is placed over the numeral $\frac{1}{2}$ on scale 32. By reading the numeral exposed by the window beneath the centerline the answer will be found. In this instance, since $\frac{1}{2}$ on scale 32 and window 31 nearest pin 19 line up in a straight line, the window will permit the viewing of the number on the column extending from the 25 foot mark which is closest to pin 19, the answer well be 200 hundredths of an inch.

In order that a person skilled in the art could provide the numerals in the various columns illustrated by reference character 27, a sample calculation will be made for the column extending from the 25 foot mark on scale 30, as was done above in computing the numerals in columns 26. The same Equation 1 is used but is rewritten as follows:

$$65 (2) \quad OM_t = (OM_f) (FL) (16)$$

By substituting the known information the following is obtained:

$$OM_t = (\frac{1}{2}) (25) (15) = 200 \text{ hundredths of an inch}$$

60 The remaining numerals in the column and the numerals in the other columns are similarly obtained.

Disc 18 is also provided with arcuate shaped scales 33 and 34. Scale 33 is divided into equal size spaces by short radially extending markings and numbered in increments of $\frac{1}{2}$ from 7 through 12. These numbers represent the most often used camera field sizes. Beside numeral 7 is placed the words "or below" which is self-explanatory. 65 Scale 34 is divided into the same number of equal spaces as scale 33 with the legend "none" placed in the space at one end of the scale and the legend "any" placed in the space at the other end of the scale. Between the two end spaces and beginning after the space marked "none," the spaces

are numbered 2° , $3\frac{1}{2}^\circ$, 6° , 9° , 12° , $15\frac{1}{2}^\circ$, 20° , 26° and $34\frac{1}{2}^\circ$. An unmarked scale 35 is positioned inwardly of scale 34. Scale 35 comprises a series of short equally spaced radially extending lines, each of said lines being aligned with pivot pin 19 and the center of one of the spaces in scale 34. The numerical value of degrees shown in scale 34 represents various maximum angles from the horizontal which the pan bars may be tilted. The relationships between scales 33, 34 and 35 may be illustrated by the fact that straight lines may be drawn through pin 19 from the numeral 7 on scale 33 to the end marking on scale 35 which is centered on the space in scale 34 having the legend "any" therein, and from the numeral 12 on scale 33 to the other end marking on scale 35 which is centered on the space in scale 34 having the legend "none" therein.

Thus, if the animator desires to determine the field size to which the camera must be moved for a given degree of tilt, it is but necessary to line up centerline 15 with the appropriate mark on scale 35 which is centered with the given degree of tilt and the answer is read from scale 33. For example, with the pan bars tilted 12° with respect to the top or bottom of the background drawing, the maximum size field on the drawing which the camera can take in without photographing the pan bars is a $9\frac{1}{2}$ field, as shown in Fig. 2. Conversely, with a given field size the animator can determine the maximum number of degrees which the pan bars can be tilted from the horizontal.

Obviously many modifications and variations of the present invention are possible in the light of the above teachings. It is therefore to be understood that within the scope of the appended claims the invention may be practiced otherwise than as specifically described.

I claim:

1. A calculating instrument for solving problems in animated motion picture layout wherein two values are known and a third value is to be solved for comprising a pair of circular discs having centrally arranged apertures therein, an elongated frame means having an aperture centrally arranged therein and a longitudinally extending centerline passing through said aperture, a pin extending through said apertures for mounting said discs on said frame means, one of said discs having a peripheral scale having numerical representations and a plurality of columns of numerals on one side thereof, each column extending radially between the central aperture of said one disc and a numerical representation on said peripheral scale, said columns being angularly spaced from each other by equal amounts, a plurality of spirally arranged windows in the other of said discs, said windows being equally spaced apart and arranged so that succeeding windows in the spiral center on succeeding numerals in said columns of numerals, and an arcuate scale on said other disc having numerical representations thereon, the arrangement being such that when the centerline is placed over the known values in said peripheral scale and said arcuate scale, the value to be solved for may be read through the window under said centerline.

2. A calculating instrument for solving problems in animated motion picture layout wherein two values are known and a third value is unknown, comprising a pair of circular discs having centrally arranged apertures therein, frame means having a pivot pin therein for receiving said apertures to rotatably mount said discs relative to said frame means, said frame means being

elongated, and having a longitudinally extending centerline therein, a peripheral scale on one side of one of said discs and having equally spaced graduations thereon, identifying indicia on each of said graduations, columns of numerals extending between the identifying indicia and the aperture of said one disc, a plurality of windows arranged in a spiral path in the other of said discs, said windows being arranged so that the window nearest the pivot pin centers on the numerals in said columns nearest said pivot pin and succeeding windows outwardly from said pin center on outwardly succeeding numerals in said columns, and an arcuate scale having identifying indicia on said other disc, the arrangement of said scales and windows being such that when one end of the centerline is placed over the graduation in said peripheral scale having an identifying indicia representing one of the known values and the other end of the centerline is placed over the identifying indicia in said arcuate scale which represents the other of said known values, the unknown value may be read from the column of numerals through the window under said one end of the centerline.

3. A calculating instrument for solving problems in animated motion picture layout wherein two values are known and a third value is unknown, comprising a pair of circular discs having centrally arranged apertures therein, frame means having a pivot pin therein for receiving said apertures to rotatably mount said discs relative to said frame means, said frame means being elongated, and having a longitudinally extending centerline therein, a scale having identifying indicia thereon positioned adjacent the periphery of one of said discs, radially extending columns of numerals extending toward the center of said one disc from said identifying indicia, a plurality of equally spaced windows arranged in a spiral path on the other of said discs, said windows being arranged to center on numerals in said columns of numerals, and an arcuate scale on said other disc having identifying indicia thereon, the relative arrangement of said scales and windows being such that by placing said centerline over the identifying indicia in said peripheral scale and said arcuate scale representing said two known values, the unknown value may be read through a window under said centerline from one of said columns of numerals.

4. A calculating instrument as in claim 3 wherein said peripheral scale has equally spaced graduations thereon with which said identifying indicia is associated, and said arcuate scale has graduations thereon which are spaced apart gradually decreasing distances from one end to the other.

5. A calculating instrument as in claim 4 wherein the windows are arranged so that the window nearest the pivot pin centers on the numerals in said columns nearest said pivot pin and succeeding windows center on succeeding numerals in said columns.

6. A calculating instrument as in claim 5 wherein the number of graduations in said arcuate scale is equal to the number of windows.

7. A calculating instrument as in claim 6 wherein the relationship between said spirally arranged windows and said arcuate scale is such that when the longitudinal centerline is placed over one end of the arcuate scale the centerline will overlie the window at one end of the spirally arranged path, and when the centerline is placed over the other end of said scale the centerline

11

will overlie the window at the other end of said spirally arranged path.

8. A calculating instrument as in claim 7 wherein succeeding graduations on said arcuate scale from one end to the other may be placed under said centerline, and when so positioned, succeeding windows from one end of said path to the other will be aligned with said centerline.

9. A calculating instrument as in claim 8 wherein the spirally arranged windows are positioned on one side of said pivot pin and said arcuate scale is positioned on the other side thereof.

10. A calculating instrument as in claim 9 wherein an additional pair of arcuate scales are 15

12

provided on said other disc, said pair of scales having angularly spaced graduations thereon and identifying indicia associated with each graduation, the graduations in each of said pair of scales being equally spaced apart and the graduations in one of said pair of scales being angularly spaced apart the same number of degrees as the graduations in the other of said pair of scales so that a known value on said one scale may be placed under the centerline and an unknown value will underlie the centerline on said other scale.
